To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

of flowers and leaves and small connected sprays of flowers and leaves following said scrolls, as shown in the drawing. A narrow 20 band formed of light horizontal lines forms the bottom of the border.

What I claim is—
